BUTTER SPREADER FOR CORN ON THE COB

Paul F. Mattar, 4562 51st St., and Howard C. Valle,
890 Cornish Drive, both of San Diego, Calif.

Filed June 11, 1962, Ser. No. 70,524

Term of patent 14 years

(Cl. D44—29)

FIG. 1

FIG. 2

FIG. 3

FIG. 4

We claim:

The ornamental design for a butter spreader for corn on the cob, as shown.
